STRAP LOCK FOR LUGGAGE

Sam Reisner, 550 Hanley Ave.,
Los Angeles, Calif. 90049

Filed Oct. 15, 1973, Ser. No. 406,629

Term of patent 14 years

Int. Cl. D8—07

U.S. Cl. D8—122

FIG. 1 is a side perspective view of a strap lock for luggage showing my new design in a position of use;

FIG. 2 is an enlarged fragmentary top plan view showing the lock portion and the end of the belt;

FIG. 3 is an enlarged fragmentary bottom plan view thereof;

FIG. 4 is a front elevational view of the strap lock for luggage in a semi-folded position;

FIG. 5 is a side elevational view thereof; and

FIG. 6 is a rear elevational view.

I claim:

The ornamental design for a strap lock for luggage, as shown and described.
